[57] CLAIM

The ornamental design for a combined vehicle side
view mirror and antenna for am/fm/cb radio and cellular
phone, as shown and described.

DESCRIPTION

FIG. 1 is a front, top and right side perspective view of
a combined vehicle side view mirror and antenna for
am/fm/cb radio and cellular phone, showing my new
design;

FIG. 2 is a reduced scale rear, bottom and left side
perspective view thereof; and,

FIG. 3 is a reduced scale rear elevational view thereof.

FIG. 1

FIG. 2

FIG. 3
